UNITED STATES PATENT OFFICE.

MICHEL E. LAPORTE, OF BORDEAUX, FRANCE.

APPARATUS FOR CLEANING RAILWAY-TRACKS.

SPECIFICATION forming part of Letters Patent No. 235,539, dated December 14, 1880.

Application filed November 9, 1880. (No model.) Patented in France July 12, 1880.

To all whom it may concern:

Be it known that I, MICHEL E. LAPORTE, master mechanic, a citizen of the Republic of France, residing at Bordeaux, in the said Republic, have invented a new or Improved Apparatus for Sweeping and Cleaning Tramway and Railway Tracks, of which the following is a specification.

This invention relates to a sweeping apparatus adapted principally for use on railroads and tramways; and it consists in the combination of a brush and a vertically-movable arm supporting said brush, said supporting-arm being at the same time capable of lateral motion, as hereinafter more fully set forth.

This invention is illustrated in the accompanying drawings, in which Figure 1 shows a front view of the apparatus as applied to a car. Fig. 2 is a detached view of a part thereof. Figs. 3 and 4 show, respectively, a front and side view of a modification. Fig. 5 is a front view of another modification. Fig. 6 is an inverted plan view of a brush.

Similar letters indicate corresponding parts. The letter *d*, Fig. 1, designates one of the supporting-beams of a car. To this beam is attached a standard, *e e*, to which is fastened one end of a spring, *a*. The other end of this spring *a* is fastened to an arm, *k*, thus holding the same in position, while said arm is at the same time free to slide up and down. This arrangement is desirable, as the body of the car is nearer to or farther from the track, according as it is heavily or lightly loaded, and the brush *l* is by this device constantly kept in contact with the rail or track. The brush *l* is further capable of vertical adjustment by means of the lever *g* swinging about the fulcrum *i*, and operated by a screw, *h*, or other suitable means.

To allow free motion of the arm *k*, the end of the lever *g*, to which said arm is jointed, is slotted or forked, as shown in Fig. 2. The other end of the lever *g* is allowed a slight play in the end of the screw *h*, to which it is attached.

The brush *l* may consist of bristles of steel wire, galvanized-iron wire, brass wire, or similar materials. These wires are kept in place by means of a metal or other suitable plate bolted to the lower part of the arm *k*. The

central part of the brush sitting in the groove of the rail is pointed at both ends, (see Fig. 6,) so as to readily pass the switches. The remaining part of the brush is adapted to throw the sweepings out and away from the track.

In case the apparatus should be attached to the body of the car and between the front and rear wheels, it is necessary that the brush be capable of lateral motion, as in passing curves, where the body of the car occupies in relation to the curved track the position of a chord in a circle, the brush would otherwise not be in contact with the track.

As shown in Fig. 1, the spring *a* and the slotted or forked end of the lever *g* permit sufficient lateral movement of the arm *k* to accomplish this purpose. Fig. 5 shows a front view of a modification.

To the car-frame *d* is firmly fastened a rod or standard, *f*. This standard *f* supports a cross-arm, *n*, having guides *o o*, in which the rod *p* is allowed to slide laterally. To this rod *p* is attached a tube, *c c*, consisting of two branches, one of which passes inside the other, and which are pressed apart by the spring *r*, thus holding the brush *l*, which is attached to the tubes *c*, down onto the track.

From the rod *p* rises an arm, *k*, which passes into a ring, *m*, which ring is rigidly attached to the standard *f*, thus limiting the lateral motion of the arm *p* and brush *l*.

In Fig. 3 the cross-arm *n* is attached to a C-spring, *b*, which spring is attached to the standard *f*. The cross-arm *n* is provided with guides *o o*, in which slides a rod, *p*. To the rod *p* the brush *l* is rigidly attached. A ring, *m*, on the standard *f*, into which passes the arm *k*, limits the lateral motion of the arm *p* and brush *l*. Fig. 4 shows a side view of Fig. 3.

The brush should be surrounded by a spreader or plow of sheet-iron or other fit material, which will assist the brush in removing the sweepings from the track. A dirt-screen in the form of a lamp-shade may also be placed about the brush.

What I claim as new, and desire to secure by Letters Patent, is—

1. In an apparatus for sweeping tramways and railroad-tracks, the combination of a vertically-movable arm provided at its lower end

with a brush and pivoted or suspended at its upper end, whereby it is capable of swinging in a lateral direction with reference to the track to retain the brush thereon, and a spring 5 acting on the brush to keep it in contact with the track, substantially as described.

2. In a track-cleaner, the combination, with a vertical arm pivoted or suspended at its upper end and capable of vertical and lateral 10 swinging movements, of a spring-impelled brush attached to the lower end of the said arm, and having its brushing-edge shaped to conform to the groove in the track, whereby

the brush is caused to travel on the latter in turning curves, substantially in the manner 15 herein described.

3. In a sweeping apparatus, the combination of a brush, *l*, vertical arm supporting said brush, and spring acting on said vertical arm, said vertical arm being jointed to a vertically- 20 oscillating lever, *g*, substantially as shown and described.

MICHEL E. LAPORTE.
